United States Patent Office

Des. 183,263
Patented July 22, 1958

183,263

ROOM HEATER OR SIMILAR ARTICLE

Edward A. Norman, Jr., Charles A. Reichelderfer, and Herman G. Raymer, Columbus, Ohio, assignors to Norman Products Company, Columbus, Ohio, a corporation of Ohio

Application December 16, 1954, Serial No. 33,578

Term of patent 7 years

(Cl. D81—19)

Fig. 1 is a perspective view of a room heater or similar article, showing our new design;

Fig. 2 is a top plan view; and

Fig. 3 is a rear side elevational view thereof.

The end wall of the room heater opposite to that shown in Fig. 1 is plain.

We claim:

The ornamental design for a room heater or similar article, substantially as shown and described.
